UNITED STATES PATENT OFFICE.

WILLIAM C. McKEOWN, OF BUFFALO, NEW YORK, ASSIGNOR TO BUFFALO RADIATOR COMPANY, OF BUFFALO, NEW YORK, A CORPORATION OF NEW YORK.

DESIGN FOR A RADIATOR.

41,811.

Specification for Design.

Patented Sept. 26, 1911.

Application filed May 23, 1907. Serial No. 375,362. Term of patent 14 years.

To all whom it may concern:

Be it known that I, WILLIAM C. McKEOWN, a citizen of the United States, residing at Buffalo, in the county of Erie and State of New York, have invented a new, original, and ornamental Design for Radiators, of which the following is a specification, reference being had to the accompanying drawing, forming part thereof.

Figure 1 is a perspective view of a radiator showing my new design. Fig. 2 is a plan view of the same.

The ornamental design for a radiator shown consists in forming each section with three vertical columns connected at their upper ends by a head, at their lower ends by a base having a central opening surrounded by a circular bead and at an intermediate point by cross-tubes; the center column having opposite sides concaved and the

sides of the outer columns being fluted and made converging to meet at the longitudinal edges of the section, the flutes being continued into the head and vanishing at the base, and the cross-tubes being concaved to conform to the concavity of the center column. The openings between columns are bounded by beads and opposing walls of said columns are beveled from said beads to a point midway between the sides of the sections. The edge of the section has a narrow projecting ridge.

I claim,—

The ornamental design for a radiator, substantially as shown and described.

WILLIAM C. McKEOWN.
